14 Claims. (Cl. 209—137)

The present invention refers to a device for the separating of stem parts from a tobacco mass, said mass being obtained by crushing tobacco leaves. The quality of the tobacco mass which is adapted for the producing of fillers is improved in a higher degree by using the device according to the invention than by using hitherto employed means for the separation.

The tobacco mass is treated in the device according to the invention in such a manner that it is conveyed by an air current through a channel which projects at least partly horizontally or upwards in the direction of said current, or the channel may be arranged in both ways. The air current is then accommodated so that the stem parts, which are heavier than the blades, fall down against the lower side of the channel, whereupon they slide down along said lower side into an opening or a collector.

20 A preferred embodiment of the invention is shown in the accompanying drawing and

Fig. 1 shows the device in a vertical longitudinal section.

25 Fig. 2 shows part of the device in a vertical front elevation and partly vertical cross section.

Figs. 3 and 4 show details of the device in a vertical longitudinal cross section respectively.

A jigger 1 projects from the front part of the housing of the device into the rear part of the 30 housing. A fan 2 is arranged below the rear end of said jigger in such a way that its outlet opening 3 has an oblique direction upwards past the rear edge of the jigger. A separating air channel projects with its lower part 4 in a somewhat 35 oblique direction upwards and backwards from an inlet opening 5 for tobacco mass formed between the lower part of the front wall 6 of the channel and the rear edge of the jigger 1. Another opening 7 is formed between the rear edge 40 of the jigger and the lower part 8 of the rear wall of the channel through which opening the fan communicates with the separator channel. An opening 9 is provided in the rear wall of the channel between an upper part 10 and the lower 45 part 8 of said wall. The channel, which converges upwards in front of the opening 9, communicates through said opening 9 with a container 11, which latter projects also below the opening 7. In the front wall 12 of an upper forwardly bent 50 part 13 of the channel is an opening 14 provided. The channel communicates through said opening by means of a channel 15 with a space above the jigger 1. The segment 13 of the channel diverges upwards in front of the opening 14.

55 Thereafter the channel is bent in a backward

direction again and the rear wall 16 of the segment 17 is provided with an opening 18 in front of which the channel converges. The opening 18 communicates through a channel 19 with the container 11. Finally the channel is again bent 60 forwardly and the front wall 20 of the segment 21 is provided with an opening 22 in front of which the channel diverges.

The opening 22 communicates through a channel 23 with a space above the jigger and it is (as 65 well as if desired also the channel 15) provided with a lid 24 pivoted at 25. Moreover an opening 26 is provided in a side wall of said channel. Thus, if desired, the upper part of the channel can by means of swinging the lid 24 to a position as shown 70 in Fig. 2 be brought out of communication with the space above the jigger and into communication with another space. Then the bottom of the channel mentioned forms an oblique surface.

The segment 21 communicates through a final 75 outlet 27 with the upper part of a drum 28 arranged behind the separated channel. Below the lower, open end of the drum 28 is arranged a container 29. A lattice or strainer 30 is provided in the rear wall of the drum.

80 The inclination of the different segments of the separating channel alter in such a way that the segment 21 runs steeper than the segment 17, which runs steeper than the segment 13, which latter runs steeper than the segment 4. Moreover the cross areas in front of the different openings are chosen in such a way, that the cross area at the upper diverging segment 21 is less than that at the lower diverging segment 13. The same is 85 valid as to the converging part 17 in relation to 90 the converging part 4 of the channel.

In order that the air currents may not form 95 any whirls in the separating channel the latter is provided with screens which convey the air in a desired direction. Such a screen is shown in Figs. 1 and 4 and indicated by 50.

The openings of the separating channel are provided with devices for regulating the separating efficiency. In the Figures 3 and 4 is shown such a device arranged e. g. at the opening 18.

100 The regulating device consists of a lid 31 pivoted on a shaft 32. The lid as well as the opening has about the same width as the channel 17. The lid at its lower end is bent round the shaft 32 and fixed to the same by means of a set screw 33. On an end 34 projecting out of the side wall 35 of the channel 17 an arm 36 is fixed. This arm is provided with a head 37 at its upper end, and said head contains a curved notch 38. A set screw 39 105 is screwed into a plate 40 attached to the side wall 110

- 35, and said plate is provided with three oblong notches 41, through which project bolts 42, fixed to the side wall 35, and provided with nuts 43 on their outer threaded ends. The two side walls of 5 the channel 17 are provided with oblong holes 44, through which the shaft 32 penetrates. Said holes are covered by the plate 40, and a ring 45 respectively, which latter as well as the plate 40 fits closely to the shaft 32.
- 10 The suction tube 46 of the fan 2 is provided with a throttle valve 47, and it is driven from a motor or the like by a belt 48 running over a step pulley 49.
- 15 The separation of the stem parts from the tobacco mass is executed in the following manner. The tobacco mass consisting of crushed blades and stems is delivered to the jigger 1 from the outlet opening of a breaker or the like. The jigger is imparted reciprocating movements (as 20 shown by the arrows). The tobacco mass is then conveyed against the rear end of the jigger, and when it falls down therefrom through the opening 5 it is encountered by an air current through the opening 7 from the fan 2 and thrown upwardly through the separator channel. The heaviest stem parts, however, cannot be thrown upwardly but slide immediately down along the rear wall 8 through the opening 7 into the container 11.
- 25 The main part of the remaining stem parts is separated from the mass at the first curve of the channel counted in the direction of the air current and the stem parts separated out slide down along the rear wall 10 through the opening 9 into the container 11. As the cross area of the segment 4 decreases in the direction of the air current the rapidity of the latter increases and thus almost entirely stem parts leave through the opening 9, as they are heavier than the blades.
- 30 The tobacco mass with possibly still therein remaining stem parts is thrown further upwardly through the segment 13, and as the cross area of this segment increases, the rapidity of the air current decreases, whereby as well stem parts as 35 parts of blades leave through the opening 14, after having滑下 along the wall 12, and descend through the channel 15 back to the jigger 1. These stem parts and blades are thus subjected to treatment in the separator channel at least 40 once more. In other words, stem parts which have not been separated out in the channel segment 4 are automatically conveyed back to the inlet opening 5.
- 45 The remaining tobacco mass is conveyed by the air current further upwardly through the separating channel, and thrown against the wall 16, so that still remaining stem parts may slide back down along said wall into the opening 18 and further descend through the channel 19 into the container 11. As the cross area of the segment 17 decreases, the rapidity of the air current increases, and entirely or at least almost entirely stem parts leave through the opening 18.
- 50 Thereafter the remaining tobacco mass ascends further upwardly through the channel segment 21, where it is thrown against the front wall 20. As the cross area of this segment increases upwardly in front of the opening 22, the rapidity of the air current decreases, and therefore as well 55 blade parts as eventually still in the mass remaining stem parts slide down along the wall 20 and further through the opening 22 and the channel 23 back to the jigger 1, whereafter it is sub- 60 jected to the separating operation again.

According to the fact that the cross areas of the diverging respectively converging segments diminish in relation to each other counted in the direction upwards the loss of air caused by leakage, etc., is counteracted. Moreover, as 8 losses of air on account of leakage cannot be avoided, the force of the current is less in the upper part of the channel than in the lower part. Therefore the resistance to the current is continuously decreased by drawing the separator channel more steep at its upper part than at its lower part. 85

If it is proved that the mass which falls down through the channels 15 and 23 consists almost entirely of stem parts, said channels may be 90 shut by a lid 24 such as shown in the channel 23 in the drawing and the opening 26 be brought into communication with the upper part of said channels. Then the stem parts slide down on the oblique surface of the lid and are thus conveyed 95 out of the channel.

The tobacco mass freed from stem parts passes through the final outlet 27 of the separator channel into the upper part of the drum 28 and falls down through said drum into the rear 100 container 29. The air leaves the drum through the strainer 30.

By means of the screens 50 it is possible to attain even air currents. If e. g. on account of uneven pressure in the channel tobacco mass 105 tends to accumulate at certain places, air currents are directed by means of the screens to such places and clogging of the channel is avoided.

By means of the regulation devices provided 110 at the outlet openings, it is possible to adjust the areas of said openings as desired. Thus, at a constant air-current through the separator channel, the output of stem parts which leave through the openings is diminished or increased 115 by diminishing or increasing the areas of the openings. The best separating efficiency is then obtained at a certain position of the lids 31. If the area then is increased or decreased, said efficiency is impaired. It is then possible to meet 120 alteration of the capacity of the fan, as well as alterations in the composition of the tobacco mass, i. e. if its contents of stem parts varies. It is of very great importance to obtain such an adjustment of the separating efficiency of the 125 device because a single type of apparatus can be manufactured, adapted for several different kinds of tobacco and adjusted after testing the apparatus to the best separating efficiency for each special kind of tobacco. 130

The adjustment of the openings is attained by swinging the lid 31 into a desired position after the screw 39 has been loosened, whereupon the screw is fastened again so that the arm 36 is fixed to the plate 40 in a certain angular position. The position of the lid 31 is adjusted at the same time because it is firmly connected to the arm 36 through the rotatable shaft 32. It is also possible to change the vertical position of the lid in relation to the opening, and 140 this is attained by loosening the nuts 43, whereupon the plate 40 may be conveyed upwardly or downwardly together with the shaft 32 and the lid 31 to a desired position, whereafter it is fixed again to the side wall 35 by fastening the nuts 145 43.

The separating efficiency may also be regulated by changing the number of revolutions of the fan or by adjusting the throttle valve 47. The regulating of the velocity of the fan is obtained 150

by means of the step pulley 49. In both cases it is possible to vary the air current through the separator channel.

It is obvious that the device now described and 5 illustrated in the drawing constitutes a special form of execution of the inventive idea underlying this application and that any other form of execution may be chosen for the purpose.

Instead of providing a fan at the inlet opening 10 of the separator channel, it is often more convenient to connect the suction side of a fan for the circulation of the air to the final outlet of the separating channel. Thereby is also the advantage obtained that even the smallest particles 15 of the tobacco mass are collected, as the air-circulation is practically closed. Besides, the advantage is obtained that the circulating air is saturated with moisture and aroma, and the quality of the tobacco is thereby improved.

20 The channel may also if desired be provided with more curves and with more than two channels for returning tobacco mass together with stem parts. If desired, the channel may have the same direction from the inlet opening to the 25 final outlet opening in the drum, whereat the channel suitably projects leaning over the inlet opening. The channel may also be composed by horizontal as well as vertical or inclined segments, and the outlet openings may be replaced 30 by collectors in the form of cavities or the like which are eventually provided with boxes or the like adapted to slide or to be tilted.

The lids 31 for regulating the separating efficiency may also be slidably arranged on the inner side of the inclined separator channel preferably on the inclined surface above the outlet opening.

What we claim is:—

1. A device for separating stem parts from 40 a mass consisting of crushed tobacco leaves having a feeding device and an air-channel provided with a supply port for tobacco mass to be treated, a discharge port for tobacco mass freed from stem parts, and a return-outlet located between 45 said supply port and said discharge port, said return-outlet communicating with the supply port.

2. A device for separating stem parts from 50 a mass consisting of crushed tobacco leaves having a feeding device and an air-channel provided with a supply port for tobacco mass to be treated, a discharge port for tobacco mass freed from stem parts, and return-outlets located between 55 said supply port and said discharge port, said return-outlets communicating with the supply port.

3. A device for separating stem parts from a mass consisting of crushed tobacco leaves having a feeding device and an air-channel provided 60 with a supply port for tobacco mass to be treated, a discharge port for tobacco mass freed from stem parts, a return-outlet located between said supply port and said discharge port and communicating with the supply port, and an escape outlet for stem parts located between said return-outlet and said supply port.

4. A device for separating stem parts from a mass consisting of crushed tobacco leaves having a feeding device and an air-channel provided 70 with a supply port for tobacco mass to be treated, a discharge port for tobacco mass freed from stem parts, a return-outlet located between said supply port and said discharge port, and communicating with the supply port, and other outlets located between said return-outlet and said

supply port, part of them communicating with the supply port.

5. In a device for separating stem parts from a mass consisting of crushed tobacco leaves having a feeding device, a substantially inclined air-channel provided with a supply port for tobacco mass to be treated, a discharge port for tobacco mass freed from stem parts, and outlets located between said supply port and said discharge port, the uppermost of said outlets communicating with the supply port. 80

6. A device for separating stem parts from a mass consisting of crushed tobacco leaves having a feeding device and a substantially inclined air-channel provided with a supply port for tobacco mass to be treated, a discharge port for tobacco mass freed from stem parts, and a return outlet located in the lower wall of an upwardly inclined part of said channel between said supply port and said discharge port, said return-outlet communicating with the supply port. 90

7. A device for separating stem parts from a mass consisting of crushed tobacco leaves having a feeding device and a substantially inclined air-channel provided with a supply port for tobacco mass to be treated, a discharge port for tobacco mass freed from stem parts, and return outlets located each in the lower wall of an upwardly inclined part of said channel between said supply port and said discharge port, said return-outlets 105 communicating with the supply port.

8. A device for separating stem parts from a mass consisting of crushed tobacco leaves having a feeding device and a substantially vertical zig-zag air-channel provided with a supply port for 110 tobacco mass to be treated, a discharge port for tobacco mass freed from stem parts and return-outlets located each in the lower wall of a segment of said channel between said supply port and said discharge port, said return-outlets 115 communicating with the supply port.

9. A device for separating stem parts from a mass consisting of crushed tobacco leaves having a feeding device and an air-channel provided with a supply port for tobacco mass to be treated, 120 a discharge port for tobacco mass freed from stem parts and a return-outlet located between said supply port and said discharge port at an extension of said air-channel and communicating with the supply port. 125

10. A device for separating stem parts from a mass consisting of crushed tobacco leaves having a feeding device, and an air-channel provided with a supply port for tobacco mass freed from 130 stem parts and with a return-outlet located between said supply port and said discharge port, and a return channel connecting said return outlet with the supply port.

11. A device for separating stem parts from a mass consisting of crushed tobacco leaves having a feeding device and a substantially inclined air-channel provided with a supply port for tobacco mass to be treated, a discharge port for tobacco mass freed from stem parts and return-outlets located between said supply port and said 135 discharge port, and communicating with the supply port, said channel having a sharper incline at a return-outlet at a higher level than at the nearest underlying return-outlet.

12. A device for separating stem parts from a mass consisting of crushed tobacco leaves having a feeding device and a substantially inclined air-channel provided with a supply port for tobacco mass to be treated, a discharge port for tobacco mass freed from stem parts and return- 140

145

150

outlets located between said supply port and said discharge port, and communicating with the supply port, said channel having a smaller cross-sectional area at a return-outlet at a higher level than at the next underlying return-outlet.

13. A device for separating stem parts from a mass consisting of crushed tobacco leaves having a feeding device, and an air-channel provided with a supply port for tobacco mass to be treated, 10 a discharge port for tobacco mass freed from stem parts and a return-outlet located between said supply port and said discharge port, and communicating with the supply port, a regulating means being provided in said return-outlet and 15 means for actuating said regulating means.

14. A device for separating stem parts from a mass consisting of crushed tobacco leaves having a feeding device, and an air-channel provided with a supply port for tobacco mass to be treated, 80 a discharge port for tobacco mass freed from stem parts and a return-outlet located between said supply port and said discharge port, and communicating with the supply port, a pivotally and axially adjustable member being arranged in said return-outlet, and means for actuating 85 said member.
